UNITED STATES PATENT OFFICE

118,146

DESIGN FOR A COMBINATION FLATIRON AND CLOTHES DAMPENER

Patrick J. Fitzgerald, Torrington, Conn., assignor to The Fitzgerald Manufacturing Company, Torrington, Conn., a corporation of Connecticut

Application August 29, 1939, Serial No. 86,926

Term of patent 14 years

To all whom it may concern:

Be it known that I, Patrick J. Fitzgerald, a citizen of the United States, residing at Torrington, in the county of Litchfield and State of Connecticut, have invented a new original, and ornamental Design for a Combination Flatiron and Clothes Dampener, of which the following is a specification, reference being had to the accompanying drawings forming a part thereof.

bination flatiron and clothes dampener showing my new design,

I claim:

The ornamental design for a combination flatiron and clothes dampener, as shown.

PATRICK J. FITZGERALD.
